[57] CLAIM

The ornamental design for a level tool, as shown and described.

DESCRIPTION

FIG. 1 is a top, front and right side perspective view of a level tool showing our new design;

FIG. 2 is a right side elevational view, the left side elevational view being a mirror image;

FIG. 3 is a top plan view;

FIG. 4 is a front elevational view;

FIG. 5 is a rear elevational view;

FIG. 6 is a bottom plan view; and,

FIG. 7 is a top, front and right side elevational view of a second embodiment of our new design of FIGS. 1-6 thereof.
